United States Patent Office

Des. 177,420
Patented Apr. 10, 1956

177,420

ATOMIZER HEAD

Elmer Lipman, Detroit, Mich.

Application May 5, 1954, Serial No. 30,334

Term of patent 14 years

(Cl. D83—1)

Fig. 2

Fig. 1

Fig. 3

Figure 1 is a vertical elevation of an atomizer head, showing my new design;

Figure 2 is a vertical elevation at right angles to Figure 1, and

Figure 3 is a top plan view.

I claim:

The ornamental design for an atomizer head, as shown.
